(57) **CLAIM**

The ornamental design for a safety cutter body, as shown and described.

DESCRIPTION

This application is related to U.S. patent appl. Ser. No. 14/608,171, entitled "Safety Cutter" filed herewith.

FIG. 1 is a left side front perspective view of a safety cutter body showing our new design;

FIG. 2 is a right side rear perspective view thereof;

FIG. 3 is a left side rear perspective view thereof;

FIG. 4 is a right side front perspective view thereof;

FIG. 5 is a left side view thereof;

FIG. 6 is a right side view thereof;

FIG. 7 is a top view thereof;

FIG. 8 is a bottom view thereof;

FIG. 9 is a front view thereof; and,

FIG. 10 is a rear view thereof.

The broken lines in the drawings show features of the safety cutter body that are included for illustrative purposes only and form no part of the claim.
